UNITED STATES PATENT OFFICE.

ORA A. COLBY, OF IRWIN, PENNSYLVANIA, ASSIGNOR TO WESTINGHOUSE ELECTRIC & MANUFACTURING COMPANY, A CORPORATION OF PENNSYLVANIA.

INDUCTION-HEATER.

1,401,673.

Specification of Letters Patent. Patented Dec. 27, 1921.

Application filed February 25, 1919. Serial No. 279,157.

To all whom it may concern:

Be it known that I, ORA A. COLBY, a citizen of the United States, and a resident of Irwin, in the county of Westmoreland and 5 State of Pennsylvania, have invented a new and useful Improvement in Induction-Heaters, of which the following is a specification.

My invention relates to induction heaters and it has, for its primary object, the provision of a heater which may be employed for heating liquids by employing a modified form of transformer which induces a heating-current of electricity in a suitable conduit.

15 My invention provides a more compact structure than has been possible with devices known heretofore. For example, it may be employed in an oil-cracking still in which it has been customary to employ 20 gas or similar fuels in supplying the necessary heat. As such fuels necessitate employing relatively large stacks to carry away the gases formed by combustion, the structure for such work may be considerably simplified 25 by employing a heater constructed in accordance with my invention.

Another object of my invention is to provide a heater for liquids and, the like, in which the heat is generated in the liquid-30 carrying passage and, in which consequently, the efficiency of the device is considerably higher than with ordinary heaters because of the heat saved by avoiding convection and other sources of loss.

35 A still further object of my invention is the provision of a heater in which the amount of heat transmitted may be automatically controlled.

With these and other objects in view, my 40 invention will be more fully described, illustrated in the drawings, in the several views of which corresponding numerals indicate like parts, and then particularly pointed out in the claims.

45 In the drawings, Figure 1 is a side view of a vertical oil-cracking still, partly in elevation and partly in section, constructed in accordance with my invention; Fig. 2 is a sectional view of the part of the still shown 50 in Fig. 1 which embodies the heating device constructed in accordance with my invention; Fig. 3 is a side elevation of a water tank and a heater therefor which embodies my invention; Fig. 4 is a detail view of the 55 heating device employed in the structure

shown in Fig. 3, and Fig. 5 is a diagrammatic view of a control system for a heating device embodying my invention.

In practising my invention, I may construct heating devices which may be embodied in a wide variety of apparatus by employing a modified form of transformer comprising a laminated core and the usual primary and secondary coils mounted thereon. However, the secondary coil constitutes 60 a conduit possessing a relatively high resistance which is contrary to the principle embodied in ordinary transformers in which the resistance of both the primary and secondary coils is usually reduced to a minimum. The secondary coil may be mounted about the laminated core between a plurality of primary coils which are, of course, insulated from each other and from the core. By supplying alternating current to the primary coils, a current may be induced in the secondary coil or conduit which, by virtue of its high resistance, is heated, thereby imparting heat to a liquid passing therethrough.

Furthermore, if it is found desirable, the heat, imparted to the liquid passing through the secondary coil, may be controlled by employing a thermostat to open or close the circuit of the primary coils, thereby controlling the heating current induced in the secondary coil.

In order to insure a clear understanding of my invention, I have shown, in Fig. 1 of the drawings, an oil-cracking still 1 comprising a suitable supporting-base 2 carrying a heating-chamber 3. The heating-chamber 3 is preferably constructed so as to provide thermal insulation for a heating device contained therein. This may be accomplished in a variety of ways; for example, the heating-chamber 3 may comprise an interior lining 4 of metal, to insure sufficient rigidity of form, and this may be covered with a suitable heat-insulating material 5.

An outlet conduit 6, provided with thermal insulation 7, may be so mounted as to extend within the heating-chamber 3 and to the end of this may be attached an annular conduit 8 which is preferably of material 105 possessing relatively high electrical resistance. An inlet conduit 9 may be attached to the annular conduit 8 diametrically opposite the conduit 6 and within the chamber 3 and may have, at its other end, a reservoir 110

10 having a drain pipe 11 and an inlet pipe 12 in which may be inserted a valve 13.

A core 14, preferably composed of superimposed laminations of steel, such as are employed in transformers, may be mounted so that one side thereof extends through the heating-chamber 3 and through the annular conduit 8. The portion of the core which passes through the heating-chamber and the 10 conduit 8 may be covered with suitable insulating material, and primary coils 15 may be mounted thereon at opposite sides of the heating-chamber.

In operating the device above described, 15 oil is forced into the inlet pipe 12, preferably under suitable pressure, through the reservoir 10 into the conduit 9 and thence into the annular conduit 8. The annular conduit 8 serves as the secondary coil of 20 the transformer and is heated by supplying electric current to the primary coils 15 which induces a current in the secondary coil, in accordance with the well known theory of transformers. A suitable current 25 is thus supplied to heat the conduit 8, thereby volatilizing and producing chemical reactions in the oil which rises through the outlet conduit 6 and is conducted into suitable vats.

30 The primary coils may be mounted at opposite sides of the heating-chamber and, being in close relation to the secondary coil, the reactance in the transformer core may be reduced. Furthermore, by so mounting 35 the primary coils, they may be insulated from the heat generated in the secondary coil which might otherwise injure their insulation.

In Figs. 3 and 4, is shown a modified 40 form of my invention and in which is illustrated a different application of it. As here shown, an ordinary water tank 16 may be provided with an inlet pipe 17 which may be wound about a transformer core 18 and led 45 to the top of the tank where it may branch into an outlet pipe 19 and an inlet pipe 20 to the tank. In this instance, the liquid-carrying pipe is given a turn or two about the transformer core 18 upon which is also 50 mounted a primary coil 21, both the primary coil and the secondary coil or pipe being insulated from the core, as indicated at 22.

The heat necessary for such service, in 55 most instances, is not excessive and the primary coil may be sufficiently insulated to protect it from any heat generated in the closely related secondary coil. The close relation of the primary and secondary coils in this modified form insures very high efficiency, as the reactance in the core is reduced to a minimum. Cold water may be supplied to the inlet pipe 17 and led through the coil wound about the transformer core 18 where it may be heated and conducted to the top of 60 the tank 16 which serves as a reservoir for the

heated water when it is not being used as fast as it is heated.

In Fig. 5 is shown, diagrammatically, a control system which may be employed in regulating the amount of heat generated in 70 the device above described. A source of alternating current supplies current to the supply line 23, to one side of which is connected a contact-member 24 which is adapted to be connected to a contact-member 26 by a bridging-member of a relay 27. The primary coil 28 of the transformer may be connected to the contact-member 26 and to the other side of the supply line 23. A switch-actuating coil 29 is connected to the 80 contact-member 24 and to a contact-member 30 which is adapted to be connected to a contact-member 31 by the bridging-member of the relay 27. A switch-actuating coil 32 may be connected in series with the primary 85 coil 28 and a thermostat 33 which is connected to the same side of the line as the free end of the primary coil.

The action of the above control circuit is 90 as follows: the bridging-member of the relay 27 connects the contact-members 24 and 26 in the heating position, thereby establishing a circuit through the primary coil to the supply line 23. The thermostat 33 may be adjusted to close the circuit which energizes 95 the switch-actuating coil 32 when the heat reaches a predetermined value and, by so doing, the relay is operated by the coil to dispose the bridging-member to close the circuit between contact-members 30 and 31, 100 and, therefore, open the circuit of the primary coil 28. When the heat has been dissipated sufficiently, the thermostat 33 closes the circuit through the contacts 31 and 30 and switch-actuating coil 29 which, when 105 energized, resets the bridging-member of the relay 27 across the contact-members 24 and 26, thus reestablishing the circuit through the primary coil to the transformer.

Although I have described a plurality of 110 structures in which a heating device embodying my invention may be employed and have set forth, in detail, structural details of the heating device, it is obvious that minor changes may be made therein and 115 many applications found therefor, and I desire that no limitations shall be imposed except such as are indicated in the appended claims.

I claim as my invention:

1. In an induction liquid heater, the combination with a metallic container for storing the liquid, of a laminated core, a primary coil on said core, a metallic tube wound around said core and forming a 125 passage for the liquid to be heated and means for electrically connecting said tube to said container.

2. An induction liquid heater comprising 130 a laminated core, a primary coil on said

core, a metallic fluid-carrying tube wound around said core and means comprising a metallic container for storing the liquid and for completing the return electrical circuit of said tube.

3. An induction liquid heater comprising a laminated core, a primary coil on said core, a metallic fluid-carrying tube wound

around said core and adapted to form the secondary coil, and means comprising a container for the liquid, for completing the electrical circuit of said tube. 10

In testimony whereof, I have hereunto subscribed my name this 20th day of Feb. 1919.

ORA A. COLBY.
